UNITED STATES PATENT OFFICE

133,222

DESIGN FOR A LAMP

Henry Rosenfeld, Cleveland, Ohio

Application April 2, 1942, Serial No. 106,429

Term of patent 7 years

To all whom it may concern:

Be it known that I, Henry Rosenfeld, a citizen of the United States, residing at Cleveland, in the county of Cuyahoga and State of Ohio, have invented a new, original, and ornamental Design for a Lamp, of which the following is a specification, reference being had to the accompanying drawing, forming part hereof, and wherein Fig. 1 is a plan view and Fig. 2 a side elevational view of a lamp showing my new design.

I claim:

The ornamental design for a lamp, as shown.

HENRY ROSENFELD.
